UNITED STATES PATENT OFFICE.

EDWIN E. SHORT, OF PRAIRIE VIEW, KANSAS.

CLOTHES-LINE SUPPORT.

980,017.

Specification of Letters Patent. Patented Dec. 27, 1910.

Application filed December 10, 1909. Serial No. 532,453.

To all whom it may concern:

Be it known that I, EDWIN E. SHORT, a citizen of the United States, residing at Prairie View, in the county of Phillips and 5 State of Kansas, have invented new and useful Improvements in Clothes-Line Supports, of which the following is a specification.

The invention relates to an improvement 10 in clothes lines and supports therefor whereby one end of the line is secured to an adjustable support by which, when desired, a line may be extended into operative position or the support folded out of the way when the line is not desired for use.

15 The main object of the present invention is the provision of a clothes line support which may be secured to a window casing and with the connected portion of the line folded into inoperative position when the 20 line is not desired for use, the extension of the support serving to tighten the line into operative condition.

Another object of the invention is the provision of means whereby the clothes pins by 25 which the clothes are supported from the line can be moved to any position on the line by simple manipulation on the part of the operator positioned adjacent the window connected end of the line, thereby permitting 30 convenient application of the clothes to the line and their adjustment on the line to the desired point.

The invention in its preferred details of 35 construction will be described in the following specification, reference being had particularly to the accompanying drawings, in which:—

Figure 1 is a view in side elevation illustrating the improved clothes line and support therefor. Fig. 2 is a plan view of the 40 adjustable support. Fig. 3 is an enlarged plan of the adjusting member for supporting the line remote from the support. Fig. 4 is a section on line 4—4 of Fig. 1.

45 Referring particularly to the accompanying drawings, my improved clothes line support comprises a frame 1 made up of upper and lower bars 2 and 3 connected at their outer ends by a plate 4 and pivotally mounted at their inner ends in brackets 5 secured to the inner surface of a suitable fixture, as for example a window casing 6. Pivotally connected to the frame 1 at a point about 50 central of the height of the plate 4 is an arm 7, to the outer end of which is pivotally con-

nected a lever 8. The inner end of the lever is pivotally mounted on a bracket 9 secured to the fixture 6 at a point remote from the bracket 5, while the outer end of the lever, which extends beyond the pivotal connection 60 of the lever and arm 7, is provided with a laterally projected section 9 formed with a series of openings 10. The arm 7 is formed with an opening 11 with which any one of the openings 10 is designed to register in the 65 movement of the parts. A pin 12 is designed to coöperate with the opening 11 and the registering opening 10.

From the construction described it is obvious that the frame 1 may be folded against 70 the fixture 6 by removing the pin 11 folding the arm connected end of the lever inwardly and drawing thereafter the frame 1, until the parts assume the position shown in the dotted lines in Fig. 2. When extended the 75 frame is projected into a position at right angles to the fixture 6, the pin 12 being inserted through an opening in the arm 7 and the registering opening 10 of the lever thereby by providing a rigid support for the frame. 80 The relatively inner edge of the plate 4 is formed with an outturned lip 13 and a groove pulley 14 is pivotally mounted on the plate beyond the lip. To the fixture remote from the structure 6, as a post 15, is secured a line 85 support including a threaded shank 16 designed to pass through the post 15, a housing band 17 in which is mounted the groove pulley 18, and an eye 19. The support is secured in the post so that the pulley 18 is in 90 line with the pulley 14 of the frame 1, and an adjusting member 20 is threaded on the rod 16 beyond the post to permit the longitudinal adjustment of the support at will. The pulleys 14 and 18 are connected by an 95 endless cable, preferably a rope 21, herein-after termed a clothes-line, and the eye 19 and lip 13 are connected by a supporting-cable 22 preferably of a suitable length of wire. Slidably mounted upon the wire 22 100 are a series of clothes pins 23 made up of spring material centrally formed to provide a spring coil 24 designed to encircle the supporting-cable 22, the material being projected from the respective ends of the coil 105 to provide clamping arms 25 arranged respectively on opposing sides of the lower length of the clothes-line, the terminals of the arms being formed to provide comparatively broad clothes engaging clamps 26. 110

Each arm 25 is provided with a finger-piece 27 arranged to permit the separation of the clamps 26 when desired to insert the clothes. It will be understood that each clothes pin is 5 normally clamped about the clothes-line by the spring coil 24, so that the pin is, when in position on the supporting-cable, also secured to the clothes-line.

In use, the frame 1 is moved to operative 10 position, and the clothes pins are successively engaged with the supporting-cable and clothes-line. One or more pins are connected to the article of clothing to be supported and the clothes-line then operated to move the 15 pins and thereby the article supported by the pins lengthwise the supporting-cable to the desired point. The device may be thus operated to utilize the full length of the supporting-cable, and the clothes when dried may be 20 conveniently removed from the clothes line by the reversal of the operation described.

It is to be particularly noted that the supporting-cable 22 is not operated, so that when initially positioned and adjusted to the desired tension will remain in such condition 25 at all times.

When not desired for use the frame may be folded as previously described to a position out of the way and this without in any 30 way effecting or requiring a disturbance of the supporting-cable or clothes-line. The tension of the clothes line may be adjusted by the adjustment of the support mounted on the post 15 as previously described.

Having thus described the invention, what 35 is claimed as new, is:—

1. The combination with a supporting-cable of a folding support including a frame, an arm pivotally connected with a frame, a pivotally mounted lever connected with the 40 terminal of said arm, and means for securing the arm and lever in adjusted relation, a remote support, a supporting-cable fixedly secured to the respective supports, a clothes-line movably connected to the respective supports, and clothes pins slidably engaging the supporting-cable and removably engaging the clothes-line. 45

2. A supporting-cable support including a frame pivotally mounted in the fixture, 50 means carried by said frame to permit the connection thereto of the supporting-cable, an arm pivotally connected to the frame, a lever pivotally connected to the fixture and to said arm, said lever being projected beyond the arm and terminally formed with a lateral section, said arm being formed with an opening, said section being formed with a series of openings adapted to register with the opening in the arm in determinate positions of the lever, and a pin to engage the registering openings. 55

In testimony whereof I affix my signature in presence of two witnesses.

EDWIN E. SHORT.
